C. H. PELTON ET AL

MOWING MACHINE

Filed Dec. 5, 1921

UNITED STATES PATENT OFFICE.

CHARLES H. PELTON AND GEORGE C. RHODERICK, OF SPRINGFIELD, OHIO, ASSIGNEES
TO THE THOMAS MANUFACTURING COMPANY, OF SPRINGFIELD, OHIO, A COR-
PORATION OF OHIO.

MOWING MACHINE.

Application filed December 5, 1921. Serial No. 520,097.

To all whom it may concern:

Be it known that we, CHARLES H. PELTON and GEORGE C. RHODERICK, citizens of the United States, residing at Springfield, in ⁵ the county of Clark and State of Ohio, have invented certain new and useful Improvements in Mowing Machines, of which the following is a specification.

Our invention relates to mowing machines, it particularly relating to improvements in the mechanism described in patent to Pelton for mowing machine, No. 943,266, dated Dec. 14, 1909.

In the patent referred to there is described ¹⁵ mechanism for adjusting the cutting devices of a mowing machine whereby the knife may be maintained in proper alignment with its actuating mechanism and also in proper registry with the stationary cutter fingers, ²⁰ and the knife and the cutter bar maintained in proper relation with the line of draft, and in that patent there is shown and described eccentric bearings for the cutter bar of an adjustable character for accomplishing ²⁵ the desired results, these eccentric bearings being clamped in split collars. When an adjustment is made, however, the relation between the walls of the split collars and the eccentric bearing blocks is necessarily ³⁰ changed as the parts must occupy a more or less angular relation relatively to each other which results in a less effective clamping area between the surface of the split collars and the blocks.

The object of our invention is to improve ³⁵ the construction of the bearing blocks and the clamping members so that an effective and uniform clamping area will be maintained between the blocks and clamping members in all positions of adjustments of the parts.

In the accompanying drawings:—

Fig. 1 is a top plan view of so much of a mowing machine as is necessary to illustrate our improvements.

Fig. 2 is a section taken on the line 2—2 of Fig. 1.

Fig. 3 is a perspective view of one of the clamping members.

Fig. 4 is a perspective view of a companion clamping member.

Fig. 5 is a perspective view of one of the bearing blocks.

Fig. 6 is a section on the line 6—6 of Fig. 1.

Fig. 7 is a section on the line 7—7 of Fig. 1.

Referring to the drawings, 1 represents a yoke which forms a part of a frame member (not shown) which supports the cutting devices. A shoe 2 of usual form is pivotally connected with this yoke and has rigidly connected therewith a conventional finger bar 3 provided with the usual fingers 4 with which co-operates a knife 5 which is carried by the bar in the usual way and has a connection through a pitman 6 with actuating mechanism of the usual form whereby the knife may be reciprocated; the knife being provided with a ball 5^a and the pitman with 70 a socket 6^a to receive the ball to form the driving connection.

Formed on the shoe, preferably as an integral part thereof, are two clamping members 7 and associated with each of these 75 clamping members is a companion clamping member 8 which is pivotally connected with the shoe. Each pair of clamping members is designed to receive and clamp a block 9 which has an eccentric aperture 10 which receives a pin 11, which pins project loosely through apertures in the arms of the yoke 1. Each block 9 has a hexagonal flange 9^a to receive a wrench whereby it may be turned for adjusting purposes.

In the present case the bearing block 9 is formed with a convex periphery 9^b and the clamping members 7 and 8 with concave bearing surfaces 7^a and 8^a to receive the convex periphery of the bearing block; the surfaces 7^a and 8^a, when the parts are in clamping position, lying diametrically opposite each other. The clamping member 8 of each pair of clamps is secured to its companion clamp 7 by a bolt 12.

By such a construction it will be seen that when either one, or both, of the blocks rotate to change the angular relation of the parts for adjustment purpose, thereby changing the angular relation of the blocks and clamping members, the clamping surfaces of the clamping members will nevertheless impinge at all effective points upon the clamping surfaces of the blocks and thereby maintain an effective clamping area between the parts, thereby obviating any danger of slippage.

of the blocks in the clamping members with consequent disarrangement of the proper adjusted position of the cutting devices.

Having thus described our invention, we 5 claim:—

1. In a machine of the character described, a support, a finger bar having a knife cooperating therewith, and a pivoted connection between said support and bar, 10 including an eccentric block and a clamp to hold the block in different positions of adjustment, said block and clamp having cooperating rounded clamping faces so formed as to permit universal movement without di- 15 minishing the effect ve clamping area of the faces, for the purpose specified.

2. In a machine of the character described, a support, a finger bar having a knife cooperating therewith, and a pivoted 20 connection between said support and bar, including an eccentric block and a clamp to hold the same in different positions of adjustment, one of the parts included in said pivotal connection having a convex clamp- 25 ing surface and the other part a cooperating concave clamping surface, for the purpose specified.

3. In a machine of the character described, a support, a finger bar having a 30 knife cooperating therewith, and a pivoted connection between said support and bar including an eccentric block and a clamp to hold the block in different positions of adjustment, said clamp consisting of a station-

ary member and a hinged member, said 35 block and clamp having cooperating rounded clamping faces.

4. In a machine of the character de- 40 scribed, a yoke-shaped support, a finger bar having a knife cooperating therewith and a 45 shoe rigidly connected therewith, a pair of sets of clamping members carried by said shoe, and an eccentric block clamped in each set of clamping members, a pivot pin con- 50 nnecting each block with said support, each of said blocks and its cooperating clamping members having cooperating concave and 55 convex clamping faces, for the purpose specified.

5. In a machine of the character de- 60 scribed, a yoke-shaped support, a finger bar having a knife cooperating therewith and a 65 shoe rigidly attached thereto, a pair of rigid clamping members on said shoe, each of said rigid clamping members having a companion 70 clamping member pivoted to said shoe, an eccentric block associated with each set of said clamping members, pivot pins ex- 75 tends through the arms of said yoke- shaped support, and eccentric apertures in 80 said blocks, said blocks and their cooperat- 85 ing clamping members having cooperating rounded clamping faces.

In testimony whereof, we have hereunto set our hands this 21st day of November 65 1921.

CHARLES H. PELTON,
GEORGE C. RHODERICK.
